United States Patent Office

Des. 205,277
Patented July 12, 1966

205,277

PIPE GASKET

Robert Fowler Gilchrist, Wichita Falls, Tex., assignor to
Vega Manufacturing Corporation, Wichita Falls, Tex.,
a corporation of Texas

Filed May 10, 1965, Ser. No. 85,205

Term of patent 14 years

(Cl. D91—3)

FIG.3

FIG.4

FIG.5

FIG. 1 is a perspective view of a pipe gasket, showing my new design;

FIG. 2 is a perspective, showing the gasket before assembly;

FIG. 3 is a top plan;

FIG. 4 is a sectional view taken along section line 4—4 of FIG. 3; and

FIG. 5 is a sectional view taken along section line 5—5 of FIG. 3;

The pipe-holding saddle and bracket shown in broken lines in FIG. 1 are included for illustrative purposes only.

I claim:

The ornamental design for a pipe gasket, as shown and described.
